[57] CLAIM

The ornamental design for a cordless telephone handset, as shown and described.

DESCRIPTION

FIG. 1 is a front elevational view of a cordless telephone handset in a closed positional configuration with the hinged microphone portion nested within the handset body, and with the antenna portion collapsed;

FIG. 2 is a rear elevational view thereof;

FIG. 3 is a top plan view thereof;

FIG. 4 is a bottom plan view thereof;

FIG. 5 is a side elevational view thereof, the opposite side being substantially the mirror image of that shown;

FIG. 6 is a front elevational view thereof in a first opened positional configuration with the hinged microphone portion unfolded to a first stable position, and with the antenna portion extended;

FIG. 7 is a rear elevational view thereof;

FIG. 8 is a side elevational view thereof, the opposite side being substantially the mirror image of that shown;

FIG. 9 is a top plan view thereof;

FIG. 10 is a bottom plan view thereof;

FIG. 11 is a front elevational view thereof in a second opened positional configuration with the hinged microphone portion unfolded to a second stable position, and with the antenna portion extended;

FIG. 12 is a rear elevational view thereof;

FIG. 13 is a side elevational view thereof, the opposite side being substantially the mirror image of that shown;

FIG. 14 is a top plan view thereof;

FIG. 15 is a bottom plan view thereof; and

FIG. 16 is a perspective view from one side of the design as now represented in FIG. 11.
